REELING DEVICE

Delmer J. Nave, Jr., and Lucius B. Herrod,
Vallejo, Calif.

Application December 13, 1945, Serial No. 634,871

1 Claim. (Cl. 242—116)

(Granted under the act of March 3, 1883, as
amended April 30, 1928; 370 O. G. 757)

1

This invention relates to reeling devices and more particularly to coiling machines.

In the handling, coiling and packing of lines, wires, cables, hawsers, ropes and other articles of similar unwieldy character, the services of several men are required. It is an object of my invention to provide an improved mechanical aid for handling such articles; to reduce the number of men required, the time involved, the space occupied, and generally to facilitate and expedite handling, coiling and reeling of such articles; to provide a mobile, power driven reel of economical construction; and to provide improved elements and arrangements thereof in a reel of the character and for the purposes set forth.

In accomplishing these and other objects of the present invention, we have provided improved details of structure, the preferred form of which is illustrated in the accompanying drawing, wherein:

The figure is a perspective view of an improved coiling machine embodying the features of the present invention.

Referring more in detail to the drawing:

A substantially rectangular base member 1, having longitudinal stringers 2, transverse stringers 3, and braces 4 is provided. Legs 5 are secured to the longitudinal stringers extending upwardly and converging to form a pair of triangular shaped supports. The base member and the legs are conveniently fabricated of tubular elements. An adjustable turnbuckle 6 is mounted so as to have one end secured to the base member and the other to a leg 5.

A bearing element 7 is mounted on the apex portion of a pair of the cooperatively employed legs. The bearing element is positioned to have its longitudinal axis substantially horizontal and parallel to the longitudinal axis of the base member 1.

An air motor 8, having a drive shaft 9 and an air supply conduit 10, is mounted on the apex portion of the other pair of legs. The drive shaft of the air motor is aligned with the longitudinal axis of the bearing element 7.

A shaft 11 is rotatably mounted in the bearing element 7 and is cooperatively connected to the air motor 8. A collar 12 is mounted on the shaft 11 in a position abutting the bearing element 7 to prevent the said shaft from being pulled from engagement with the air motor during operation. The bearing 7, motor 8 and shaft 11 are so arranged to dispose outwardly one end of the shaft 11 in a position free from interference from the base member 1 or legs 5.

2

A reel member, comprising a coaxial flange portion 13 and a frusto-conical drum portion 14 of lesser diameter, is fixedly mounted on the freely disposed portion of the shaft 11 so as to be supported and rotated thereby. The drum portion is preferably fabricated from spaced tubular elements permitting access to the interior of the drums between the elements. This type of construction facilitates securing articles coiled on the drum, as by tying. The drum portion 14 has its end of lesser diameter positioned toward the free end of the shaft 11 to permit the expeditious removal of wires, cables, hawsers, ropes and other similar articles reeled on the drum.

15 To prevent such articles from sliding from the drum 14 during operation, a removable flange 15, similar in size and shape to the flange 13, is provided. The removable flange 15 is of sufficiently greater diameter, than the drum portion 14, to retain articles reeled thereon when secured in an 20 abutting relationship to the drum portion. To assist in positioning and securing the flange 15 in place for operation, the said flange is mounted on a sleeve element 16 which is telescopically 25 engaged to the shaft 11. A set screw 17 is provided to lock the sleeve element 16 and flange 15 in position on the shaft.

Operation

30 The operation of a coiling machine constructed as described is as follows:

The coiling machine of this invention being of light and mobile construction is easily positioned in respect to the cable or similar article to be 35 coiled.

The flange 15 and sleeve 16 are slid on to the outwardly disposed shaft 11 to a position abutting the drum portion 14. The set screw 17 is rotated to engage the shaft 11 and secure the said sleeve 40 and flange in operating position.

A running end of an article of the character described to be coiled is secured to the reel portion of the coiling machine at the end of lesser diameter of the frusto-conical drum portion 14.

45 The shaft 11 and reel portion attached thereto are caused to rotate by the motor 8. The article being coiled is fed onto the reel as the reel is caused to rotate.

When the desired amount of coiling is accomplished, the rotation of the reel and shaft is halted. The reeled material is bound in its coiled condition to hold it in shape when removed from the coiling machine. This is accomplished by an attendant using his hand to 55 pass short lengths of small line, commonly called

stops, through the cutout openings between the sectors of the flanges 15 and 13 and thence beneath the innermost layer of the coil lying on the drum portion 14 and then tying the ends of these stops together to bind the coil. This process is called "stopping" the coil. The set screw 17 is backed away from engagement with the shaft 11 and the sleeve 16 and flange 15 are removed from the shaft. The coiled article is then facilely removed from the frusto-conical drum portion 14 in the form of a tied coil that is easy to handle.

It has been found that the frequent loading of the reel and shaft 11 tends to cause a displacement of the legs 5 by the strain imparted thereto. When such displacement occurs, the tightening of the turnbuckle 6 is found to strengthen the support provided for the motor 8, bearing 7, shaft 11, reel member and coiled material.

While we have shown but one embodiment of our invention, it is susceptible to modification without departing from the spirit of the invention. We do not wish, therefore, to be limited by the disclosures set forth, but only by the scope of the appended claim.

The invention described herein may be manufactured and used by or for the Government of the United States of America for governmental purposes without the payment of any royalties thereon or therefor.

We claim:

In a device of the character described, a shaft having a driving end and a free end; a reel member mounted on said shaft for rotation therewith; said reel member comprising a drum portion and a flange member; said drum portion including a plurality of spokes lying generally along elements of the frustum of a cone described,

about the axis of said shaft and tapering toward the free end of said shaft; said flange member being located at the larger base of said frustum and having a plurality of cutout portions extending radially inward from its periphery; a removable flange member adapted to be placed over the free end of said shaft in abutting relation to the smaller end of said drum portion and having cutout portions extending radially inward from the periphery of said flange member; and means for detachably fixing said removable flange to said shaft to rotate therewith, said means comprising a sleeve unitary with said removable flange member and adapted to be received by said shaft and means carried by said sleeve for direct driving engagement with and disengagement from said shaft, said cutout portions in said flanges being so proportioned and so located relative to said spokes as to provide free access for the hand of an attendant beneath the first layer of a coil of line wound on said reel member and completely around the thickness of the coil whereby the coil may be stopped in a plurality of places while the coil remains on the winding drum.
